(57) **CLAIM**

The ornamental design for a housing for an ion generator, as shown and described.

DESCRIPTION

FIG. 1 is a top perspective view of a first embodiment of a housing for an ion generator showing the new design; FIG. 2 is a bottom perspective view of the design of FIG. 1; FIG. 3 is a front view of the design of FIG. 1; FIG. 4 is a rear view of the design of FIG. 1; FIG. 5 is a first side view of the design of FIG. 1; FIG. 6 is a second side view of the design of FIG. 1; FIG. 7 is a top view of the design of FIG. 1; FIG. 8 is a bottom view of the design of FIG. 1; FIG. 9 is a top perspective view of a second embodiment of a housing for an ion generator showing the new design; FIG. 10 is a bottom perspective view of the design of FIG. 9;

FIG. 11 is a front view of the design of FIG. 9; FIG. 12 is a rear view of the design of FIG. 9; FIG. 13 is a first side view of the design of FIG. 9; FIG. 14 is a second side view of the design of FIG. 9; FIG. 15 is a top view of the design of FIG. 9; and, FIG. 16 is a bottom view of the design of FIG. 9.

The broken lines shown represent the portions of the housing for an ion generator that form no part of the claimed design.
